ENGINE DRIVEN CHAIN SAW

Elmer C. Kickhaefer, Cedarburg, Wis.

Application October 7, 1948, Serial No. 53,201

6 Claims. (Cl. 143—32)

1

This invention relates to engine driven chain saws and particularly to the manual system of controls for such saws.

A principal object of the invention is to provide for the greater safety of the operator of the saw and reduce the possibility of accidental injury by providing engine and clutch controls which are more simple and easily operated.

Another object is to more fully assure the complete safety of the operator by providing engine and clutch controls which are instantly accessible.

Another object is to provide for the full and complete ease of control of the chain saw in any cutting position.

Another object is to provide for the use of the saw in any cutting position without changing the grasp of the control handle from one hand to the other.

Another object is to provide a finger tip control of the engine speed which is not exposed to accidental disadjustment and is nonetheless easily accessible in any cutting position.

Another object is to provide for the disengagement of the clutch of the chain saw unit as in the event that the operator has lost control of the saw, by contact of the clutch control with any part of the operator's body.

These and other objects and advantages of the invention will be more fully set forth in the following description of a preferred embodiment of the invention as illustrated in the accompanying drawings.

In the drawings:

Figure 1 is a view of the chain saw unit approximately from the position of the operator;

Fig. 2 is an enlarged view of the underside of the unit showing the operator's controls;

Fig. 3 is a sectional view of the control handle with parts thereof broken away and sectioned and showing the same in the position of clutch engagement and with the throttle lever set at full throttle;

Fig. 4 is a view similar to Fig. 3 showing the handle locked in the position of clutch disengagement and with the throttle at slow speed;

Fig. 5 is an enlarged detail section of the clutch taken axially of the engine crankshaft and the sprocket shaft showing the sprocket engaged for operation of the unit;

Fig. 6 is a perspective view of the chain saw unit generally from one side and as supported upon a flat surface; and

Fig. 7 is a side view of the chain saw unit showing the side opposite that of Fig. 6 and with the longitudinal axis of the guide rail extending

2

horizontally and the abutment member engaging a log shown in dotted lines.

The chain saw unit shown in the drawings comprises the engine 1, the flat guide rail 2 extending forwardly of the unit and secured to the transmission case 3 at the one end of engine 1, and the saw chain 4 carried by rail 2 around the edge thereof.

The engine 1 includes the carburetor 5 and the ignition control wire 6.

The sprocket 7 carried by the hollow shaft 8 is disposed adjacent the end of rail 2 and carries the chain 4 around the end of rail 2 to drive the same. Shaft 8 is driven as will be described by the gear 9 which meshes with the pinion 10. Pinion 10 is formed within the engine crankshaft 11 of engine 1 between bearings 12 carrying one end of the crankshaft. The gear 9 is mounted to rotate in the bearing 13 within transmission case 3. Shaft 8 is journally mounted within transmission case 3 by the bearing 14 near the end carrying sprocket 7 and is carried at the opposite end by the needle bearing 15 within gear 9 to rotate freely with respect to the latter. The clutch element 16 which provides a positive drive connection between shaft 8 and gear 9 comprises a circular member having a pair of bosses 17 on the side adjacent gear 9. Element 16 is secured on shaft 8 for rotation therewith by means of the splines 18 which allow axial movement of element 16 relative to shaft 8 and the selective engagement and disengagement of the bosses 17 with gear 9 within the recesses 19 in the opposite side of the gear.

The spring 20 within shaft 8 is disposed between the plug 21 at the outer end of shaft 8 and the cross pin 22 carried by element 16 within slots 23 of shaft 8 and extending through the shaft. Spring 20 normally biases pin 22 and clutch element 16 in one direction for engagement with gear 9. The push pins 24 and 25 are disposed within shaft 8 and at the side of pin 22 opposite spring 20 and are adapted to be engaged by the cam 26 to push the pin 22 and element 16 in the opposite direction out of engagement with gear 9. Preferably pins 24 and 25 are of brass and steel respectively to provide suitable bearing surfaces upon relative rotational movement. The shaft 27 carries cam 26 adjacent the end of shaft 8 for engagement with the end of pin 25 projecting from the end of shaft 8.

The spring 28 mounted on shaft 27 biases the shaft and cam 26 rotationally normally to allow engagement of clutch element 16 and gear 9.

The lever 29 on the outer end of shaft 27 is connected to means under the control of the operator as will be described to effect selectively the rotation of shaft 27 against the biasing of spring 28 and of cam 26 thereby moving pin 22 within shaft 8 and the clutch element 16 in and out of engagement with gear 9.

The chain saw unit is adapted to be operated by one man and to be disposed with rail 2 in either horizontal or vertical positions of operation for cutting. In operation, chain 4 is driven at high speed on rail 2 and moves on the lower side of rail 2 toward the engine and operator holding the unit. The cutting is intended normally to be done by that portion of the chain on the lower side of rail 2. The horn 30 projects downwardly at the end of rail 2 secured to engine 1 and is adapted to be engaged by the timber through which the chain is moving and cutting to carry the thrust of the unit normally in a direction away from the operator. The rail 2 extending forwardly of the unit is set at one side of the unit to allow cutting close to the ground without obstruction.

The tubular handle 31 secured to engine 1 extends freely over and downwardly on opposite sides of the chain saw unit and is secured to the engine beneath the unit to be grasped at the side uppermost with either the right or left hand of the operator in either of the two horizontal or vertical cutting positions. Handle 31 is located with respect to the center of gravity of the unit so that in operation the support of the saw is provided almost entirely by handle 31 allowing for manipulation of the unit and control of engine 1 by means of a second control handle as will be described. The arrangement of handle 31 provides for the easy carrying and transporting of the saw in a normal balanced position. The rubber sheath 32 on handle 31 provides for easier gripping of the handle without slipping.

The control handle 33 secured to engine 1 on the rear side, opposite guide rail 2, comprises a single cast or stamped member. Handle 33 having a suitable opening 34 is of the "pistol grip" type which is shaped to conform to the full grasp of the hand and is disposed centrally at the rear of the chain saw unit to be grasped with either the right or left hand.

The clutch control 35 comprises preferably a stamped member of U-section disposed on the back side of handle 33 and which is pivotally secured thereto at the upper end of the handle. Control member 35 is dimensioned to conform generally to the shape of the hand and is adapted to be squeezed or pressed forwardly over handle 33 with the palm of the hand grasping the handle.

The control rod 36 connected to the lower end of control member 35 extends beneath handle 33 and forwardly of the unit and is operatively connected to the clutch lever 29 to control the driving connection of engine 1 and the saw chain 4. The rod 36 connects control member 35 and lever 29 so that when clutch control member 35 is pressed forwardly as with the palm of the hand against the biasing of springs 28 and 20, the clutch element 16 and gear 9 are disengaged and the chain is operatively disconnected from the engine.

The latch 37 pivotally mounted within control member 35 near the lower end thereof is biased by the spring 38 to engage the abutment 39 in the lower end of handle 33 when control member 35 is pressed forwardly, securing the member against movement and the clutch in disengagement. The sliding thumb piece 40 at the upper end of member 35 is connected by the rod 41 75

therein to latch 37. Thumb piece 40 is disposed to be slidably moved upwardly with the thumb of the hand grasping handle 31 to disengage latch 37 allowing spring 28 to move member 35 rearwardly effecting engagement of clutch element 16 and gear 9.

The throttle lever 42 pivotally mounted at the upper end and forwardly of handle 33 within opening 34 is biased forwardly by the spring 43 and is adapted to be engaged with the index finger of the hand grasping handle 33. The gear segment 44 rotating with lever 42 engages the pinion 45 on shaft 46 which is connected to shaft 47 of carburetor 5 to control the engine fuel supply. Lever 42 is biased by spring 43 so that the engine runs at slow speed when lever 42 is released and accelerates as the lever is moved rearwardly against spring 43.

The throttle lock 48 pivotally mounted on handle 33 is provided with a pin 49 adapted to be moved downwardly into engagement with pinion 45 in one direction and secure the same against rotation in the opposite direction and throttle lever 42 in the selected position of adjustment. Lock 48 operates so that when depressed against the biasing of the spring 50, the pin 49 moves into and is secured in locking engagement with pinion 45, and by pressing lever 42 rotating pinion 45 against the biasing of spring 43, pin 49 is released to allow further adjustment of the carburetor.

The electrical push button switch 51 recessed in the top of handle 33 is connected by the wire 6 to the ignition system to stop the engine upon depressing of the switch.

The lever 53 conveniently provided at one side of handle 33 controls the carburetor fuel mixture.

The recoil hand starter 54 is provided at the side of the unit at the end of engine 1 opposite transmission case 3. Starter 54 is actuated by manual pulling of handle 55 upwardly and rearwardly of the unit while the latter is supported on members 31 and 35 and one hand of the operator grasps the top of handle 31 above the unit to hold the same.

When operating the chain saw unit in either of the upright, inverted or either horizontal position, the clutch and carburetor controls and ignition switch are disposed relative to handle 33 within easy reach of the hand and fingers grasping the handle.

In the event that the operator should lose control of the saw the clutch can be instantly disengaged by pressing member 35 with the arm or leg to stop the chain. Control member 35 is disposed immediately in front of the operator at all times and can be operated with the knee as when, in certain instances, the saw unit is held with both hands grasping the tubular handle 31.

Handle 33 is disposed so that the saw can be easily held properly against the thrust of the chain and with the horn 30 against the timber being cut. In the event that the timber should bind the upper part of the chain causing the saw suddenly to move out of the kerf toward the operator, control member 35 will usually be automatically pressed by the hand grasping handle 31 to automatically move and maintain the clutch elements in disengagement.

The control handle is intended to be used by both right and left handed persons. The simplicity of the control system makes it easy for both right and left handed persons to learn and acquire quickly the necessary "feel" of the saw. The control of the saw is the same in any cutting

position so that no unfamiliarity is experienced on the part of the less skilled operator when cutting in difficult positions. The arrangement of the handles lessens fatigue on the part of the operator thereby further reducing the possibility of accidental injury.

The motion necessary to disengage the clutch in case of emergency is the same for all positions and becomes quickly a reflex action on the part of the operator.

The arrangement of the handles further allows the saw chain to be placed fully to one side with respect to the unit without unbalance of the unit in the hands of the operator and enables the chain saw unit to be so designed for making cuts close to the ground or other obstructions without waste.

Various embodiments of the invention may be employed within the scope of the accompanying claims.

I claim:

1. In a portable lightweight engine-driven chain saw unit, having an engine, a saw chain disposed forwardly of the engine, and a clutch operatively connecting said engine and chain; a clutch control carried by and disposed rearwardly of the unit and oppositely of the chain respecting the unit, said clutch control comprising relatively movable members one of which is fixed to the unit and the other of which is connected to said clutch to actuate the same, said clutch being engaged when said members are separated and said clutch being disengaged when said members are closed together, said members being disposed to provide a single handle for manipulation of the unit with one hand and arranged to disengage the clutch when the members are moved to closed position upon a tight grasping of the members with the hand as in an emergency.

2. In a portable engine-driven chain saw unit having an engine, an endless saw chain extending forwardly of the unit, and a clutch operatively connecting said engine and said chain to drive the latter; control means for said unit comprising a fixed guide handle connected to and disposed rearwardly of the unit for manipulating the unit and a lever operatively connected to said clutch to control engagement and disengagement of the clutch and pivotally connected to the unit and disposed rearwardly of the guide handle and adjacent thereto, said clutch being engaged when said lever is pivoted rearwardly away from said handle and being disengaged when said lever is pivoted forwardly toward said handle, and biasing means yieldably holding said lever in a rearward position for clutch engagement and operation, said lever being pressable forwardly respecting the unit and toward said handle to effect immediate clutch disengagement as in the event of binding of the chain in the kerf causing movement of the unit against the lever or by grasping said control means tightly in the hand.

3. In a portable engine-driven chain saw unit having an engine, a saw chain, a clutch operatively connecting said engine and said chain, and a chain guide rail rigidly secured to and extending forwardly of the unit; a grasping rail extending substantially around the unit at the center of gravity thereof and providing a series of hand holds for manually supporting the unit and the chain guide rail in any one of several cutting positions by either hand; control means for said unit comprising a fixed guide handle connected to and disposed rearwardly of the engine for manipulating the unit and a lever oper-

atively connected to said clutch to control the same and pivotally connected to the engine and disposed rearwardly of the guide handle and adjacent thereto and rearwardly of the unit so that in any one of the said cutting positions the lever is operatively exposed for operation from the rear of the unit as by contact with the operator or a fixed object at the rear of the unit, said clutch being engaged when said lever is pivoted rearwardly away from said handle and unit and being disengaged when said lever is pivoted forwardly toward said handle and unit, a spring yieldably holding said lever in a rearward position for clutch engagement and operation, said lever being pressable forwardly respecting the unit and toward said handle to effect immediate clutch disengagement as in the event of rearward movement of the unit or by grasping said control means tightly in the hand, and cooperating latch means carried by said handle and lever and disposed to secure said lever in clutch disengaged position and releasable to allow movement of said lever for reengagement of said clutch.

4. In combination with the structure of claim 3, wherein an engine control lever disposed adjacent to and forwardly of said fixed handle to be engaged by a finger of the hand grasping said handle in any one of said cutting positions.

5. In a one-man portable lightweight engine-driven chain saw unit, an engine having a transmission case, and a chain guide rail rigidly secured to said transmission case and extending forwardly of the unit; a series of hand holds including a rail member extending circumferentially of the longitudinal axis of said guide rail and adjacent to the center of gravity of the unit, said member being secured at the bottom of the unit to said transmission case and extending across the bottom of the unit and spaced from and along the sides of the engine and secured thereto to protect the engine when accidentally dropped, the upper of said series of hand holds being disposed transversely and above the unit with respect to said guide rail and adjacent the center of gravity of the unit, and rigid supporting means including a single guide handle connected to the unit rearwardly thereof oppositely of said guide rail, said series of hand holds and said guide handle means providing respectively for the major support of the unit with the guide rail disposed forwardly thereof in any of several cutting positions and the manipulation of the unit for advancing or withdrawal of the guide rail respecting the cut, the lower parts of said rigid supporting means and said rail member extending beneath the unit to rigidly support the latter on the ground as for starting the engine and the like with the unit tilted rearwardly and the guide rail elevated from the ground to locate the upper hand hold vertically of and between the lower part of said rail member and said rigid supporting means, whereby the upper hand hold may be utilized to hold the unit steady upon the lower part of the rail member and supporting means when starting the engine as with a recoil starter.

6. In a lightweight, engine-driven portable chain saw unit adapted to be supported and operated by one man, and including an engine having a transmission case, a guide rail rigidly secured to the transmission case and extending forwardly of the unit, an endless cutting chain carried by the guide rail, and an abutment provided at the forward end of the transmission case and adjacent to the lower portion of the chain im-

mediate thereto, the lower portion of said chain being driven by the engine in a direction toward the abutment and the opposite portion of the chain being subject to binding by pinching thereof in the kerf in which event the unit tends to be propelled by the engine in the direction of the operator and rearwardly of the unit; control means for the unit comprising a fixed guide handle connected to and disposed rearwardly of the unit and adjacent to the operator oppositely of the guide rail and chain, and handle means including a rail member secured to the unit and providing a series of hand holds extending circumferentially of the longitudinal axis of the guide rail and adjacent to the center of gravity of the unit, said handle means including a hand hold above the unit and substantially above and vertical of the abutment when the unit is upright for advancing the saw chain into a vertical cut pivotally about the portion of the abutment engaging the work, said handle means providing for the major support of the unit near the center of gravity thereof with the guide rail disposed forwardly in either the vertical or any of several cutting positions to allow the relatively free ma-

nipulation and control of the unit by said control means.
